UNITED STATES PATENT OFFICE

153,970

DESIGN FOR A SHIRT

Joseph Nachman, Philadelphia, Pa.

Application March 19, 1948, Serial No. 145,209

Term of patent 3½ years

(Cl. D3—25)

To all whom it may concern:

Be it known that I, Joseph Nachman, a citizen of the United States, residing at Philadelphia, in the county of Philadelphia and State of Pennsylvania, have invented a certain new, original, and ornamental Design for a Shirt, of which the following is a specification, reference being had to the accompanying drawing, forming part thereof:

In the drawing:

Fig. 1 is a front view of a shirt showing my new design.

Fig. 2 is a rear view of the shirt shown in Fig. 1.

Fig. 3 is an enlarged fragmentary view of one of the sleeves showing my new design.

I claim:

The ornamental design for a shirt, substantially as shown.

JOSEPH NACHMAN.
